UNITED STATES PATENT OFFICE.

GEORGE I. SCHREIBER, OF NEWARK, NEW JERSEY.

PHOTOGRAPHIC-FILM-SUPPORTING FRAME.

1,391,982.

Specification of Letters Patent. Patented Sept. 27, 1921.

Application filed September 21, 1920. Serial No. 411,709.

To all whom it may concern:

Be it known that I, GEORGE I. SCHREIBER, a citizen of the United States, residing at Newark, in the county of Essex and State of New Jersey, have invented certain new and useful Improvements in Photographic Film-Supporting Frames; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention has reference, generally, to improvements in photographic film supporting frames; and the invention relates, more particularly, to a novel construction of film strip carrying frame for holding roll film strips in unrolled and stretched position while undergoing the processes of development.

The invention has for its principal object to provide a simple, cheap, easily manipulated and efficient film strip supporting or carrying frame, for holding one or more film strips unrolled and stretched out while being submitted to the developer baths, rinsing and fixing baths, and while being dried.

The invention has for a further object to provide a novel construction of adjustable supporting frame which possesses novel film engaging means for holding the films by their ends in properly unrolled and stretched out condition, so that the same may be submitted to the various development processes without liability to curling, scratching or other detrimental effects upon the same, and which, furthermore, affords a very convenient and rapid means for handling the films throughout the various steps of the development processes.

Other objects of the invention, not at this time more particularly enumerated, will be clearly understood from the following detailed description of the same.

With the various objects of the present invention in view, the same consists, primarily, in the novel construction of photographic film strip supporting or carrying frame hereinafter set forth; and the invention consists, furthermore, in the novel arrangements and combinations of the various devices and parts, as well as in the de-

tails of the construction of the same, all of which will be hereinafter more fully described, and then finally embodied in the claims appended hereto.

The invention is clearly illustrated in the accompanying drawings, in which:—

Figure 1 is a face view of my novel film strip supporting or carrying frame, made according to and embodying the principles of my present invention; Fig. 2 is a vertical longitudinal section through the same, taken on the line 2—2 in said Fig. 1; Fig. 3 is a detail transverse section of the lower end of the frame, showing the means for mounting adjustable film engaging elements therewith, the latter being shown in elevation; and Fig. 4 is a detail cross section of a portion of the means for engaging the ends of the film strip, showing the mounting of the retaining pins or piercing points thereof.

Similar characters of reference are employed in all of the hereinabove described views, to indicate corresponding parts.

Referring now to said drawings, the reference character 1 indicates the complete film strip supporting or carrying frame, made according to and embodying the principles of my present invention, the same comprising a pair of longitudinally disposed parallel side bars or rods 2. The lower ends of said side rods 2 are connected together by means of a transverse bottom bar 3, which preferably consists of a flat metal strip or bar, into which the lower ends of said side rods 2 are riveted. The upper ends of said side rods 2 are connected together, at points spaced downwardly from but adjacent to their extremities, by means of a transverse top bar 4, which preferably consists of a round metal bar, having eye-ports 5 formed at its ends through which respectively extend said side rods 2. The upper free ends or extremities of said side rods 2 are respectively provided with outwardly and laterally projecting arms 6.

Secured by their lower ends, which extend into and through said bottom bar 3, so as to project upwardly from the latter between said side rods 2, are a series of pairs of parallel tubular guide members 7. Slidably related to each pair of tubular guide members 7 is a longitudinally adjustable film strip engaging member, comprised of an inverted U-shaped device consisting of a

cross-bar 8 and integrally connected depending longitudinal legs 9. Said legs 9, when free, tend to slightly diverge from a parallel relation, so that when the same are 5 inverted respectively in the respective members of a pair of the parallel tubular guide members 7, the same will frictionally engage the latter so as to retain themselves in any position of longitudinal adjustment 10 relative to said guide members, while, nevertheless, being free to move longitudinally in either direction when subjected to pressure sufficient to overcome such frictional engagement, so that the adjustable 15 film strip engaging members may be readily moved to adjust the same to the length of film to be mounted on the supporting or carrying frame, although adapted to retain such adjusted position whereby the film 20 strip may be held properly stretched out in unrolled condition. Secured in the cross bar 8 of each film strip engaging member are a plurality of film strip engaging or piercing pins or points 10, which project 25 downwardly from said cross bar 8, and which preferably incline outwardly from the perpendicular.

Secured in said top bar 4, at points 30 opposed to the position of each film strip engaging member, are a plurality of film strip engaging or piercing pins or points 11, which project upwardly from said top bar 8, and which preferably incline outwardly from the perpendicular in the same direction as do 35 the pins or points 10 of the adjustable film strip engaging members.

In utilizing the novel construction of film strip supporting or carrying frame, constructed as above described in detail, the 40 free or outer end 12 of a roll of film strip 13 is engaged with the top bar 4, by thrusting said end 12 over the pins or points 11, so that the latter pierce through the same. The film strip 13 is unrolled, so that it extends 45 downwardly toward the opposing adjustable film strip engaging member, to the cross bar 8 of which is attached the lower end 14 of said film strip, by thrusting said end 14 over the pins or points 10, so that the latter pierce through the same. The adjustable film strip engaging member 50 is thereupon pressed downwardly in its tubular guide members 7, to stretch the film strip straight and flat, and to thereupon hold the same under the desired tension 55 whereby the same is secured tautly against curling, etc.

It will be apparent that the novel supporting or carrying frames will support one 60 or more film strips in desired tautly stretched out position, so that by immersing the frame in a developer tank (in which position the frame is supported or hung from the edges of the tank by the arms 6) the 65 film surface is adequately exposed to the

action of the developer fluid. After development the frame can be readily removed from the developer tank, and thence immersed in a rinsing tank, subsequent to which the same is removed and immersed in 70 the fixing bath. The film supporting frame, when removed from the fixing bath, may again be rinsed, and then the frame may be suspended in any convenient place while the film strips are dried. It will thus be seen 75 that the supporting or carrying frame serves to hold the film strips during all the steps of the developing processes, with a minimum of handling so that the work can be rapidly carried on, and at the same time the films 80 are held securely against curling or warping, and are less liable to rub against one another whereby scratching or injury to the negatives might occur.

I am aware that some changes may be 85 made in the arrangements and combinations of the various devices and parts, as well as in the details of the construction of the same, without departing from the scope of my present invention as set forth in the 90 foregoing specification and as defined in the appended claims. Hence, I do not limit my invention to the exact arrangements and combinations of the various devices and parts as described in said specification, nor 95 do I confine myself to the exact details of the construction of the said parts as illustrated in the accompanying drawings.

I claim:—

1. In a device of the kind described, a 100 frame comprising side rods, a top bar and a bottom bar, upwardly projecting piercing pins connected with said top bar upon which one end of a film strip may be engaged, and adjustable film strip engaging means connected with said bottom bar, said engaging means having downwardly projecting piercing pins upon which the opposite end of a film strip may be fastened, said engaging means being movable longitudinally to 105 stretch tautly the body of said film strip.

2. In a device of the kind described, a frame comprising side rods, a top bar and a bottom bar, upwardly projecting piercing pins connected with said top bar upon which one end of a film strip may be engaged, guide means mounted on said bottom bar, an inverted U-shaped adjustable member having its legs slidable through said guide means, said legs of said member frictionally 115 engaging said guide means to hold the former in the position to which it is adjusted, and said adjustable member having downwardly projecting piercing pins upon which the opposite end of a film strip may be 120 fastened.

3. In a device of the kind described, a pair of longitudinal side rods, a transverse bottom bar secured to the lower ends of said side rods, a transverse top bar secured to 125 130

- the upper portions of said side rods, the free ends of said side rods above said top bar having outwardly turned lateral supporting arms, upwardly projecting piercing pins connected with said top bar upon which one end of a film strip may be engaged, tubular guide means mounted in said bottom bar, an inverted U-shaped adjustable member having its legs slideable through said 5 guide means, said legs of said member frictionally engaging said guide means, to hold the former in the position to which it is adjusted, and said adjustable member having downwardly projecting piercing pins 10 upon which the opposite end of a film strip may be fastened.
4. In a device of the kind described a rectangular open frame having fixed means at one end for engaging one end of a film strip, and an inverted U-shaped member mounted 20 for longitudinal adjustment in the lower end of said frame, said member having means for engaging the opposite end of a film strip to hold the latter stretched tautly in unrolled condition. 25

In testimony that I claim the invention set forth above, I have hereunto set my hand this 16th day of September, 1920.

GEORGE I. SCHREIBER.
